UNITED STATES PATENT OFFICE.

ADDISON J. GALLIEN, OF UPPER MONTCLAIR, NEW JERSEY, ASSIGNOR TO R. HOE AND CO., OF NEW YORK, N. Y., A CORPORATION OF NEW YORK.

MARGINAL PRINTING.

Application filed September 3, 1921. Serial No. 498,196.

To all whom it may concern:

Be it known that I, ADDISON J. GALLIEN, a citizen of the United States, residing at Upper Montclair, county of Essex, and 5 State of New Jersey, have invented certain new and useful Improvements in Marginal Printing, fully described and represented in the following specification and the accompanying drawings, forming a part of the 10 same.

This invention relates to certain improvements in the form and arrangement of printing plates on a printing plate support, and the invention has for its special object 15 the form and arrangement of a printing plate so that the usual margin space between two plates may be utilized for printing without a break in the printing surface of this margin space.

It is frequently desirable in printing certain products that the margin space usually formed between two adjacent printing plates be utilized for printing, as, for instance, in printing double wide pages with- 20 out a center margin or in utilizing the space for late news, advertisements, or matter different from that contained in the main body of the page. It has been proposed to accomplish this by casting two plates, each 25 with a projecting portion substantially one half the width of the margin space, the two plates abutting about the center of the clamp or clip used for holding the plates on the plate support. With this construction 30 both plates had to be cast with these extending portions. Furthermore, with this construction a line was produced centrally of the margin space due to the gap between the adjacent edges of the plates. When this 35 construction was utilized for printing advertisements or late news, this line would run through such printed matter, and for this reason this construction was undesirable.

A construction is provided by the present 45 invention whereby the whole of the margin space may be utilized for printing without this central line so that the space may be used for late news, advertisements, etc., with a smooth, unbroken surface, and a construction requiring but one specially cast 50 plate. A preferred construction for effecting this is illustrated in the accompanying drawings, in connection with which the invention will now be described in detail, and

the novel features pointed out in the claims 55 hereunto annexed.

In the drawings,—

Figure 1 is a longitudinal section through a portion of a plate cylinder showing two plates in the position they occupy for ordinary printing with margin space between; 60

Figure 2 is a section taken on line 2—2 of Fig. 1;

Figure 3 is a longitudinal sectional view 65 similar to Fig. 1, showing the improved construction for utilizing the margin space;

Figure 4 is a partial, diagrammatic plan view of a part of a newspaper printed with the arrangement of Fig. 1 showing the margin left on the web or sheet; 70

Figure 5 is a diagrammatic plan view of a portion of a newspaper page printed with the construction shown in Fig. 3, the printing shown in Fig. 5 being that of a two page wide sheet or web without center margin; 75

Figure 6 is a diagrammatic plan view of a part of a newspaper page printed with the construction of Fig. 3, showing the center margin space utilized for printing matter 80 different from that in the main body of the paper, this margin space being completely utilized without a broken line therein.

Referring now to the drawings, the invention has been illustrated as employed in 85 a construction in which the plate support is a cylinder, but it will be understood that the invention is applicable to forms other than those supported on cylindrical or curved supports.

In the construction illustrated, referring first to Figs. 1 and 2, the plate support is shown as a portion of a cylinder marked 1. In the construction shown there are two plates 2, 3, supported on this cylinder, these 95 plates being formed as ordinarily, with bevelled edges 4 which take under the bevelled sides 5 of a margin ring 6. This margin ring 6 forms a part of the means for clamping the plates on the cylinder, and the width 100 of this ring provides the margin. In the construction shown this margin ring is separate from the cylinder and is movable longitudinally of the cylinder as is usual where a cylinder 4 plates wide is employed. It is to be understood, however, that this margin ring may be made integral with the cylinder, where a cylinder carrying two 105

2

plates wide is used. This margin ring is secured by screws 7 to a clip block 8 and a shaft 9, this shaft being operated in any suitable manner, not shown, to move longitudinally of the cylinder and lock the plates in position against the ring. A stop nut 10 is or may be provided for limiting the endwise movement of the shaft and the block. This margin ring, however it may be secured in position on the cylinder, is lower than the slide of the plate, so as to provide a margin space against which there will be no impression. A web printed with the construction illustrated in Fig. 1 will produce 15 a product such as shown in Fig. 4, in which a margin space is indicated by the letter N.

In carrying out the invention, to utilize this margin space for printing as above set forth so as to produce the products shown in 20 Figs. 5 and 6, one of the plates, as the plate 2, will be cast or otherwise formed with an extension 11, this extension being wide enough to extend entirely, or substantially entirely across the margin space and over 25 the margin ring and to abut against the bevelled edge 4 of the plate 3, the lower inner edge of the extension being bevelled as indicated at 12 so as to make a snug contact with the edge of the plate 3, the extension 30 of the plate resting on and being supported by the ring. This plate 2 is formed beneath the extension 11, with an under-cut portion 14 so that it will take under the edges 5 of the margin ring and be clamped 35 firmly in place by operating the clamp shaft 9 as before referred to. With this construction a product such as shown in Fig. 5 may be produced with the columns extending unbrokenly across a two page wide sheet, 40 the extension of the plate 2 being prepared with the proper printing matter. Further, if desired, the product illustrated in Fig. 6 may also be produced, in which the main pages 15, 16 of the product may be printed with 45 the usual matter and the space 17 ordinarily occupied by the margin may be printed with matter different from that of the main pages without a central break. Furthermore, it is only necessary to obtain these products 50 to prepare one plate with the extension instead of preparing two plates.

While the invention has been shown in its best form, it will be understood that various means may be employed for clamp-

ing the plates in position on the cylinders 55 and various arrangements of the plates on the cylinder may be made, and the invention is not intended to be limited to the exact construction and arrangement shown and described. 60

What is claimed is:

1. The combination with a printing plate support, of a plate stop on the support and normally spacing two adjacent plates to form a margin space therebetween, and a pair of plates on the support, one of said plates having an extension projecting entirely across the margin space and providing an unbroken printing surface in such space. 70

2. The combination with a printing plate support, of a plate stop on the support, and a plate on the support having an extension projecting entirely across the plate stop and abutting against an adjacent plate on the other side of the stop and providing an unbroken printing surface across the stop. 75

3. The combination with a printing plate support, of a plate stop on the support, a plate having an extension projecting entirely across the stop, the outer edge of said extension being bevelled and abutting against the bevelled edge of a plate on the other side of the stop, and the inner edge being formed with a shoulder taking against 80 a cooperating shoulder on the stop, the extension of the plate forming an unbroken printing surface where it projects across the stop. 85

4. The combination with a plate support, 90 of main printing surfaces on the support, a plate stop on the support between the main printing surfaces and spacing them to form a margin, and a printing surface narrower than the main surfaces and extending entirely across the margin space and providing an unbroken printing surface in such space. 95

5. A printing plate formed with a main printing surface and a shoulder adapted to engage a margin stop, and an extension projecting beyond the shoulder at one side of the plate dimensioned to extend across the stop, said extension having an unbroken printing surface for printing in the margin space formed by the stop. 100

In testimony whereof, I have hereunto set my hand.

ADDISON J. GALLIEN.
